UNITED STATES PATENT OFFICE.

EDWARD B. ALLEN, OF BRIDGEPORT, CONNECTICUT, ASSIGNOR TO THE SINGER MANUFACTURING COMPANY, A CORPORATION OF NEW JERSEY.

POWER-TRANSMITTING MECHANISM.

1,372,475.

Specification of Letters Patent. Patented Mar. 22, 1921.

Application filed April 14, 1919, Serial No. 289,851. Renewed June 14, 1920. Serial No. 389,005.

To all whom it may concern:

Be it known that I, EDWARD B. ALLEN, a citizen of the United States, residing at Bridgeport, in the county of Fairfield and State of Connecticut, have invented certain new and useful Improvements in Power-Transmitting Mechanisms, of which the following is a specification, reference being had therein to the accompanying drawings.

- 10 In the sewing rooms of garment factories, it is common practice to arrange the sewing machines in rows at opposite sides of so-called "power-tables," the machines being spaced apart along the tables and belted up to driving pulleys arranged at intervals along line-shafts disposed lengthwise of and beneath the tables. To meet the requirements of factory inspectors, a power-table is usually provided with suitable 15 screens or protective devices which close off the space below the table-top and obstruct access by the machine operators to the line-shafts, pulleys, belts, or other power-transmission devices. Consequently the driving 20 pulleys on the line-shaft are permanently belted to the respective driving elements of suitable clutch devices commonly used for starting and stopping the machines.
- 25 If, for any reason, certain of the machines on a given power-table are not being used, the transmission devices connected thereto are subjected to much wear and tear which could be obviated were the power-table 30 equipped with means whereby the operator could, conveniently and with safety, interrupt and reestablish driving relation between the driving belts and their respective driving pulleys. Also, in threading up certain 35 types of sewing machines, particularly automatic buttonhole sewing machines, it is necessary to turn the machines over by hand until the parts are in accessible positions. In the case of an automatic machine 40 controlled by a stop-motion device, it is necessary to throw off the driving belt and trip the stop-motion before the machine can be turned over by hand to threading position. This necessity has, in the past, put 45 the machine operators to much inconvenience and has occasioned the loss of much time, to say nothing of the well known dangers incident to working with the driving 50

mechanism below a power-table while the line-shaft is in motion.

55

The object of the present invention is to provide a power-table of the class described with means readily accessible to the operator of a given machine whereby the driving relation between the driving pulley on the line-shaft and the belt normally driven thereby, may be quickly, safely and conveniently interrupted or established, without necessitating removal or displacement of any of the parts of the protective screening with which such tables are usually equipped.

A further object of the invention is to provide a power-table with means conveniently accessible to the operator whereby the driving belt may be thrown off of the driving pulley and relieved of tensile stresses, or thrown onto said driving pulley, and retained in either position without further attention on the part of the operator.

Still further, the invention has for an object to provide power-transmitting mechanism of the character described which may be readily installed and operated regardless of the direction of rotation of the power-shaft.

80

Further objects of the invention will appear from the following description and claims.

The objects of the invention are attained by the present construction wherein the driving pulley is formed with a belt-groove and carries a belt-retaining guide-ring or plate which is parallel to and spaced from the driving pulley, whereby the belt may contract somewhat and assume a loose position when thrown from the driving pulley, yet will be retained in a position favorable to the ready reestablishment of driving relation between said pulley and belt. In the present instance a manually controlled belt-shifting device is provided for throwing the belt onto or off of the driving pulley. To facilitate the shifting of the belt, the pulley is provided with a radial, outwardly projecting, belt-catching tooth. The belt-shifting device includes a belt-shifting guide and adjustable supporting means therefor affording capacity for installation and adjustment to operative position either in front of or behind the power-shaft, as the direction of rotation of the latter may in-

100

105

dicate. These parts are disposed mainly within the protected space beneath the table-top and are connected with an operating handle accessible exteriorly of said space or, in other words, at the front of the table.

In the accompanying drawings, Figure 1 is a side elevation of a portion of a power-table embodying the invention. Fig. 2 is 10 a fragmentary transverse vertical section through the power-table. Fig. 3 is a sectional view of the pulley taken on the line 3—3 of Fig. 4. Fig. 4 is a cross section of the pulley taken on the line 4—4, of Fig. 3. 15 Fig. 5 is a perspective view of one of two similar disks for adjustably carrying the belt-shifting guides.

In the preferred embodiment of the invention, as illustrated, the power-table comprises a table-top 1 and the usual supporting means 2 carrying the shaft-hanger 3 in which is journaled the constantly running driving or power-shaft 4; said shaft being disposed beneath and lengthwise of the 25 table-top in the customary manner disclosed, for example, in United States Patent to H. Eichhorn and R. Becker, No. 1,223,681, of April 24, 1917. In practice the power-table supports two rows of machines, one 30 row at each side of the table, and each machine is driven from its individual driving pulley on the line shaft 4. However, inasmuch as the various driving connections between the line-shaft and any one of the 35 machines are merely duplicates of similar driving connections for the various other machines, a description of a single driving unit will suffice for the purposes of the present disclosure.

40 Clamped to the line-shaft 4 is the split pulley 5 having a deep V-shaped belt-groove 6, one of the side walls 7 of which is cut away at 8—8 to facilitate passage of the belt onto and off of the pulley when 45 rotated in either direction. A radially extending belt-catching tooth 9 is secured to the side wall 7 of the belt-groove between the recesses 8—8. This tooth is bent outwardly, away from the pulley, as shown in 50 Fig. 1. Fixed to the pulley 5 are the spacing studs 10 which support the belt-retaining disk or plate 11 in parallel relation to the pulley.

Supported on the table-top 1 is a machine 55 12 to be driven; the particular machine illustrated being an automatic buttonhole sewing machine of the type represented in my Patent No. 1,240,642, of Sept. 18, 1917, or in my copending application Serial No. 60 204, 842, filed Oct. 1, 1917. Machines of this type embody the usual start and stop-motion device 13 for controlling the period of action of the stitch-forming mechanism including the reciprocating needle *n*. The 65 start and stop-motion device 13 includes a

loose pulley 14 which heretofore has been permanently belted to the driving pulley and consequently was forced to run continuously even though the particular machine was not in use.

In the present instance the pulley 14 is connected by the belt 15, running over idlers 16, to the driving pulley 5. When shifted to non-running position the belt lies loosely in the space between the pulley 5 and retaining plate 11, as shown in Figs. 1 and 2. In this position the belt is held out of the range of the belt-catching tooth 9 by means of the belt-shifting guide 17 adjustably mounted in a socketed holder 17^a which, in turn, is adjustably mounted upon the upwardly and rearwardly extending rod 17^b the lower end of which is fixed in an apertured edgewise projecting lug 17^c of a disk 17^d bolted flatwise against the circular ear 17^e at the free end of the carrier-bar 18. The bar 18 is pivoted at 19, 19, to the upstanding parallel links 20 which at their lower ends are fixed to pivot pins 21 journaled in the upstanding ears 22 of the base-plate 23 screwed to the 90 floor *f*.

Secured to one of the pivot pins 21 is an arm 24 which is connected by means of the link 25 and bell-crank 26 with the inner end of a rod 27, the outer end of which is bent 95 to the form of a handle 28 disposed beneath the edge of the table exteriorly of the protected space below the table-top defined by the guard *s*.

To determine the limits of movement of 100 the belt-shifter in either direction, the hub of the arm 24 is formed with a short arm 29 the extremity of which is adapted to strike one or the other of the stop-screws 30 carried by the base 23.

Whenever use of the machine is to be discontinued for a time, the operator pushes the rod 27 inward, thus shifting the belt 15 out of the belt-groove 6 of the driving pulley 5 and into the space between the pulley 5 and the belt-retaining disk 11; the belt being held beyond the path of movement of the belt-catching tooth 9 by the belt-guide 17. By virtue of the use of the parallel links 20 the belt-shifting guide 17 supported thereby will 110 partake of a movement of translation. Thus the running and non-running positions in the belt-shifting guide 17 will be parallel to each other.

A leaf-spring 31 secured to the under side 120 of the table-top 1 bears yieldingly upon the rod 27 to hold the belt-shifting device in either running or non-running position with the arm 29 in engagement with one or the other of the stops 30. The operator may 125 therefore leave the machine with the belt disconnected from the constantly running line-shaft 4 which, at the time, may be driving various other machines.

In the particular structure chosen for the 130

purpose of this disclosure, the machine 12 is provided with a shaft 32 for operating the buttonhole cutting mechanism with which such machines are usually provided. 5 This mechanism is commonly actuated from a constantly rotating pulley 33 through an automatic one-rotation clutch device 34. In the present instance the pulley 33 is shown as belted up to a pulley 35 on a short countershaft 36 carrying a larger pulley 37 which is connected by a belt 37' to a driving pulley 38 on the power-shaft 4. The pulley 38 is of substantially the same construction as the pulley 5 hereinbefore described, and 15 comprises the belt-catching tooth 39 and the belt-retaining disk 40. The belt 37' is shifted onto or off of the pulley 39 by means of a belt-guide 41 which is constructed and adjustably carried by the carrier-bar 18 in 20 the same manner as the belt-shifting guide 17 previously described. By virtue of the translatory movement of the carrier 19 there is no objectionable tilting of the belt-shifting guides 17 and 41 carried thereby, even 25 though such guides are spaced apart a considerable distance along the shaft 4.

In the event that the shaft 4 is driven in the reverse direction, the belt-shifting guides and supporting devices can readily be installed in rear of the shaft 4 and adjusted to operative position; the provision of the similar disks 17^a, rods 17^b and holders 17^c permitting ready installation and adjustment of the belt-shifting guides to operative position relative to the driving pulleys whether placed in front of or behind the shaft 4. The driving pulleys having their belt-catching teeth disposed radially and provided with recesses at opposite sides of said teeth, 40 will catch and throw on the respective driving belts when rotated in either direction.

Having thus set forth the nature of the invention, what I claim herein is—

1. In power-transmitting mechanism, in combination, a driven pulley, a grooved driving pulley, a belt connection between said pulleys, a belt-retainer spaced from said driving pulley, a belt-catching tooth projecting laterally toward said belt-retainer, and a belt-shifting device for throwing the belt onto the driving pulley or into the space between said driving pulley and belt-retainer.

2. In power-transmitting mechanism, in combination, a driven pulley, a grooved driving pulley, a belt connection between said pulleys, a belt-retainer spaced from said driving pulley, a belt-catching tooth projecting laterally toward said belt-retainer, a belt-shifting device for throwing the belt onto the driving pulley or into the space between said driving pulley and belt-retainer, and means for detaining the belt-shifting device in either running or non-running position.

3. In power-transmitting mechanism, in combination, a driven pulley, a grooved driving pulley, a belt connection between said pulleys, a belt-retaining ring spaced from said driving pulley, a belt-catching tooth carried by said pulley and projecting laterally toward said belt-retaining ring, and a belt-shifting device for throwing the belt onto the driving pulley or into the space between said driving pulley and belt-retaining ring. 70

4. In power-transmitting mechanism, in combination, a driven pulley, a grooved driving pulley, a belt connection between said pulleys, a belt-retaining ring in the form of a plate-like disk parallel to and spaced from said driving pulley, a belt-catching tooth carried by said pulley and projecting laterally toward said belt-retaining disk, a belt-shifting device for throwing the belt onto the driving pulley or into the space between said driving pulley and belt-retaining plate, stops for limiting movement of the belt-shifting device in either direction, and means for holding the belt-shifting device in engagement with either of said stops. 85

5. In power-transmitting mechanism, a driven pulley, a grooved driving pulley having a belt-catching tooth, a belt connection between said pulleys, a belt-shifting guide, a guide-carrier, parallel links pivotally supporting said guide-carrier, and manually controlled means for swinging said links. 95

6. In power-transmitting mechanism, a power-shaft, a plurality of driving pulleys spaced along said shaft, a plurality of driven pulleys belt connected with their respective driving pulleys, a plurality of belt-shifting guides, a guide-carrier, parallel links pivotally supporting said guide-carrier, and manually controlled means for swinging said links. 105

7. In a power-table, in combination, a table-top, supporting means therefor, constantly running power means journaled beneath the table-top and including a grooved driving pulley having a laterally projecting belt-catching tooth, a guard at the front of said table obstructing ready access to the power means, a machine to be driven stationed on the table-top, a belt connection between said machine and the driving pulley, belt-shifting means stationed mainly in an inaccessible position behind said guard and including a manually controlled device extending through said guard and accessible to the operator at the front of the table, whereby the belt-shifting device may be thrown to running or non-running position, and means for maintaining the belt-shifting device in either of the positions to which it may be shifted by the operator. 115

8. In power-transmitting mechanism, in 120

combination, a power-shaft, a grooved driving pulley carried by said power-shaft and having a belt-catching tooth operative to throw on the belt when the power-shaft is 5 rotated in either direction, and belt-shifting mechanism including a belt-shifting guide and adjustable supporting devices therefor adapted for installation and adjustment to operative position at either side of 10 said power-shaft.

9. In power-transmitting mechanism, in combination, a power-shaft, a grooved driving pulley carried by said shaft, a driven pulley, a belt connection between said pulleys, said driving pulley having a radial 15 belt-catching tooth and depressions at op-

posite sides of said tooth, and belt-shifting means adapted for coöperation with said pulley to throw the belt to running or non-running position.

20

10. In power-transmitting mechanism, in combination, a power-shaft, a grooved driving pulley carried by said shaft, a driven pulley, a belt connection between said pulleys, said driving pulley having a radial 25 belt-catching tooth and depressions at opposite sides of said tooth, and a belt-shifting guide for controlling that limb of the belt which runs onto the driving pulley.

In testimony whereof I have signed my 30 name to this specification.

EDWARD B. ALLEN.
